UNITED STATES PATENT OFFICE.

GEORGE JOSEPH MACK, OF BROOKLYN, NEW YORK, ASSIGNOR TO U. S. INDUSTRIAL ALCOHOL CO., A CORPORATION OF WEST VIRGINIA.

CLOSURE.

Application filed January 19, 1921. Serial No. 433,363.

To all whom it may concern:

Be it known that I, GEORGE JOSEPH MACK, a citizen of the United States, residing at Brooklyn, in the county of Kings and State 5 of New York, have invented a certain new and useful Improvement in Closures, of which the following is a specification.

My invention relates to closures generally but particularly to covers designed for closing tank cars and it has application also to other covers of the same general character as for example warehouse doors.

The object of my invention is to provide a cover or door of the kind above referred 15 to which is provided with a locking mechanism that will effectively prevent unauthorized access through the same.

The object is especially to provide an effective locking means which cannot be readily broken as would be the case if the locking mechanism were situated on the outside of 20 the enclosure and were secured to the same by a flexible attaching means.

A further object is to provide a locking 25 mechanism for such covers or doors which is so arranged that the lock cannot be opened without the necessity of breaking a seal which in this instance is a revenue stamp that is situated over the keyhole of the locking mechanism located on the inside of the 30 cover or door.

Still another object is to provide a locking mechanism of this character which is located on a cover screw-threaded in the 35 dome of the tank car.

Further objects will appear from the detailed description of the invention herein-after contained.

There are many ways of carrying out my 40 invention but I have shown one form of the same in the accompanying drawings, in which—

Figure 1 is a vertical section of a dome plate carrying a cover made in accordance 45 with my invention.

Figure 2 is a bottom plan view of the same.

Figure 3 is a plan view of the lock carried by the cover.

50 Figure 4 is a plan view showing the interior mechanism of the same.

Figure 5 is a section taken on line 5—5 of Figure 3.

Figure 6 is a section taken on line 6—6 55 of Figure 5.

Figure 7 is a plan view of the stamp carrying device.

Figure 8 is a plan view of the same in opened position.

Figure 9 is a plan view of the key-hole 60 plate fitting on the inside of the cover.

Figure 10 is a plan view of the key which is used for operating the lock.

In the drawings I have shown a dome plate 1 having a plurality of holes 2 around 65 its edge to permit the same to be riveted to the dome of the tank car. The dome plate 1 has an opening 3 surrounded by a downwardly directed screw-threaded flange 4 to receive a screw-threaded flange 5 fitting 70 therein carried by a cover 6. The cover 6 has a lifting handle 7 at its center and a rotating handle 8 near its edge, as well as a plurality of ears 9 having holes 10 therein to aid in the moving of the cover. Around 75 the periphery of the cover there may be a gasket 11 of leather or other similar material which fits against an annular projection 12 on the dome plate 1 to make an air-tight joint. Furthermore, the cover 6 has a number of laterally directed holes 13 to act as 80 vents in opening the tank car.

Attached to the inside of the cover 6 there is a lock casing 14 which is held in place by screws 15. The lock casing 14 has a laterally movable bolt 16 adapted to pass through an opening 17 in the flange 5 into a recess 18 in the dome plate 1. This lock may be of any desired construction but by way of example it may have the following operating 90 parts, in addition to the bolt referred to above. The bolt 16 is carried by a sliding plate 19 fitting against the bottom of the lock casing 14, which has a guiding slot 20 cooperating with a projection 21 on the 95 lock casing. Said plate 19, furthermore, is provided with a recess 22 to cooperate with a member 23 on a key 24 which is adapted to be inserted over a stem 25 on the lock casing that fits into the barrel of the key. 100 Upon the sliding plate 19 there is a projection 26 that projects into an opening 27 located in three tumblers 28, said tumblers being pivoted upon a pin 29 carried by the lock casing. These tumblers, furthermore, 105 have springs 30 which rest against a stop 31 on the lock casing. The stop 31 is provided with a screw-threaded recess and there are two similarly recessed members 32 and 33 on the lock casing. These three recessed 110

members support a diaphragm plate 34 which is held in place by screws 35. The plate 34 has holes 36 for the passage of the screws 15, a hole 37 for the pin 29 and a key-hole 5 38 to receive the key 24. Furthermore said plate has at one end thereof a slot 39 into which projects a flange 40 on a sliding plate 41, in such a manner that the flange 40 normally rests upon the rear end of the bolt 16. 10 The plate 41 is guided by means of a strap 42 screwed to the diaphragm plate 34 and is normally pressed forwardly by means of a spring 43 surrounding a rod 44 on the rear of the plate 41 which rod passes through a 15 hole 45 in the lock casing 14. Upon the top of the sliding plate 41 there is an inverted L-shaped catch 46 which is arranged to cooperate with an apertured tongue 47 arranged to project downwardly through the cover 6 20 and carried by a hinged key-hole plate 48. The said key-hole plate is hinged to a stationary key-hole plate 49 secured to the top of the cover by means of screws 50 passing through the same, through the cover and 25 into an inner key-hole plate 51. The inner key-hole plate 51 has a slot 52 to permit the passage of the apertured tongue 47 and a key-hole 53 to permit the entry of the key. The stationary key-hole plate 49 has 30 a similar aperture 54 for the tongue 47 and a key-hole 55 for the key. Said plate 49, furthermore, has four recesses 55¹ over which a revenue stamp 56 is designed to be placed and locked in position by four correspond- 35 ing pins 57 carried by the hinged key-hole plate 48 around key-hole 58. Again, upon the top of the hinged key-hole plate 48, there is a rotary cover 59 supported by a pivot 60 on which there is located a coiled spring 40 61 resting in a recess 62 in the rotary cover 59, so that the cover 59 will normally occupy a position over the key-hole 58.

In the operation of my invention, after the tank car has been filled with the liquid 45 to be shipped, the cover 6 is placed over the same either with the aid of the ears 9 or the handle 7, or both, and is then screwed into place by use of the handle 8 until the gasket 11 fits against the top of the flange 50 12 and the bolt 16 is opposite the recess 18 in the dome plate 1. Thereupon the key 24 is inserted and the bolt 16 is moved into the recess 18 thus locking the cover in place. The key is then withdrawn and a revenue 55 stamp is placed over the key-hole 55, after which the hinged key-hole plate 48 is moved into its lower position, thus causing the apertured tongue 47 to engage with the L-shaped projection 46 which springs into the 60 aperture in the tongue 47 due to the pressure of the spring 43. This at the same time holds the stamp 56 in place over the key-hole 55 and perforates it with the aid of the teeth 57. In order to gain access to the tank 65 car now it is necessary to first swing the

cover 59 to one side and then insert the key into the lock through the key-hole 58, the revenue stamp 56 and the key-holes 55, 53 and 38. Whenever the tank car is opened in this way or an unauthorized attempt is 70 made to gain access thereto by inserting opening devices into the lock, the opening or attempted opening of the tank car can be readily seen by the fracture of the revenue stamp 56. Furthermore, it would be 75 extremely difficult to gain access to the tank car without the proper key as it would be a difficult matter to in any way move or damage the locking mechanism because of its location on the interior of the tank car 80 cover. The presence of the screw-threaded flanges 4 and 5 which engage with one another, strengthens the locking mechanism in a very effective manner also. Once, however, that the bolt 16 has been withdrawn 85 by the operation of the lock with the key 24, the cover 6 may be readily unscrewed so as to give access to the tank car, and by the withdrawal of the bolt 16 the tongue 47 will be released from the projection 46, thus permitting the hinged key-hole plate 48 to be moved outwardly so that the old stamp can be removed. The parts are now in position for closing the tank car again in the manner above described. 90

Above I have described my invention in detail, but it is to be understood that many changes will be made therein within the scope of my invention. 95

I claim:

1. A cover for tank cars having a locking mechanism fixedly mounted thereon, said locking mechanism having a movable locking member, a key for operating the same and a movable stamp-holding key-hole plate 105 constructed to be held in place by the locking mechanism so as to prevent the removal of the stamp when locked by the locking member.
2. A cover for tank cars having a screw-threaded fastening means and a locking mechanism fixedly mounted thereon, said locking mechanism having a movable locking member, a key for operating the same and a movable stamp-holding key-hole plate 115 constructed to be held in place by the locking mechanism so as to prevent the removal of the stamp when locked by the locking member.
3. A cover for tank cars having a locking 120 mechanism fixedly mounted thereon, said locking mechanism having a movable locking member, a key for operating the same and a movable stamp-holding key-hole plate 125 constructed to be held in place by the locking mechanism so as to prevent the removal of the stamp when locked by the locking member, said stamp being positioned so as to cover the key-hole.
4. A cover for tank cars having a screw- 130

threaded fastening means and a locking mechanism fixedly mounted thereon, said locking mechanism having a movable locking member, a key for operating the same and a movable stamp-holding key-hole plate constructed to be held in place by the locking mechanism so as to prevent the removal of the stamp when locked by the locking member, said stamp being positioned so as to cover the key-hole.

5. A cover for tank cars having a locking mechanism located on the interior thereof, said locking mechanism having a movable locking member, a key for operating the same and a movable stamp-holding key-hole plate having a depending portion held in place by a catch actuated by the locking mechanism so as to prevent the removal of the stamp when locked by the locking member.

15 6. A cover for tank cars having a screw-threaded fastening means and a locking mechanism located on the interior thereof, said locking mechanism having a movable locking member, a key for operating the same and a movable stamp-holding key-hole plate having a depending portion held in place by a catch actuated by the locking mechanism so as to prevent the removal of the stamp when locked by the locking member.

20 7. A cover for tank cars having a locking mechanism located on the interior thereof, said locking mechanism having a movable locking member, a key for operating the same and a movable stamp-holding key-hole plate having a depending portion held in place by a catch actuated by the locking mechanism so as to prevent the removal of the stamp when locked by the locking member, said stamp being positioned so as to cover the key-hole.

25 8. A cover for tank cars having a screw-threaded fastening means and a locking mechanism located on the interior thereof, said locking mechanism having a movable locking member, a key for operating the same and a movable stamp-holding key-hole plate having a depending portion held in place by a catch actuated by the locking mechanism so as to prevent the removal of the stamp when locked by the locking mem-

ber, said stamp being positioned so as to cover the key-hole.

9. The combination of a movable locking member comprising a combined bolt and spring catch, a key for the same, and a movable stamp-clamping plate having a member adapted to be engaged by the spring catch when locked.

10. A closure having associated therewith a fixed locking mechanism, said locking mechanism having a movable locking member, a key for operating the same and a movable stamp-holding key-hole plate constructed to be held in place by the locking mechanism so as to prevent the removal of the stamp when locked by the locking member.

15 11. A closure having a locking mechanism fixedly mounted thereon, said locking mechanism having a movable locking member, a key for operating the same and a movable stamp-holding key-hole plate constructed to be held in place by the locking mechanism so as to prevent the removal of the stamp when locked by the locking member.

20 12. A closure having a locking mechanism located on the interior thereof, said locking mechanism having a movable locking member, a key for operating the same and a movable stamp-holding key-hole plate constructed to be held in place by the locking mechanism so as to prevent the removal of the stamp when locked by the locking member.

25 13. A cover for tank cars having a screw-threaded fastening means and a locking mechanism located on the interior thereof, said locking mechanism having a movable bolt, a key for operating the same, a two-part hinged key plate, one part of which may be swung back on the hinge to admit a stamp between the two plates, a depending portion on the movable plate, a catch actuated by the said bolt for locking the said depending portion when the tank is locked, and a spring for moving the catch into locking position.

30 35 40 45 50 55 60 65 70 75 80 85 90 95 100 In testimony that I claim the foregoing, I have hereunto set my hand this 6th day of January, 1921.

GEORGE JOSEPH MACK.
